HAROLD O. HOLTE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 31, 1924. Serial No. 729,211.

My invention relates to railway traffic controlling apparatus, and particularly to apparatus of the type comprising train carried governing apparatus controlled by energy received from the trackway. More particularly, my invention relates to apparatus of such type in which the train carried apparatus comprises vibration or tuned reed relays.

I will describe two forms of railway traffic controlling apparatus embodying my invention, and will then point out the novel features thereof in claims.

In the accompanying drawings, Fig. 1 is a diagrammatic view showing one form of railway traffic controlling apparatus embodying my invention. Fig. 2 is a view showing one modification of the apparatus illustrated in Fig. 1 and also embodying my invention.

Similar reference characters refer to similar parts in both views.

Referring first to Fig. 1, the reference characters 1 and 1^a designate the track rails of a railroad over which traffic normally moves in the direction indicated by the arrow. These track rails are divided, by means of insulated joints 2, into a plurality of successive track sections A—B, B—C, etc. Each track section is provided with a track circuit including a track relay and a track transformer. Each track relay is designated by the reference character K with an appropriate exponent and is connected across the rails adjacent the entrance end of the associated section. Each track transformer is designated by the reference character T with an exponent corresponding to the location and has a secondary winding 5 connected across the rails adjacent the exit end of the associated section. An impedance 4 is interposed, as usual, between the secondary 5 of each track transformer and one rail 1^a of the corresponding section.

Each section is further provided with a trackway signal designated by the reference character S with a suitable distinguishing exponent. These signals S may be of any suitable form and as here shown are three position semaphore signals each capable of indicating proceed, caution or stop. These signals are controlled by means not shown in the drawing. The control of these sig-

nals S forms no part of the present invention, and it is sufficient for present purposes to state that each signal is so controlled that when the corresponding section is occupied, the signal indicates stop; when the corresponding section is unoccupied but the section next in advance is occupied, the signal displays a caution indication, and when the corresponding section and the section next in advance are both unoccupied, the signal indicates proceed.

Associated with each signal S is a circuit controller 9 so operated that contact 9^a—9^a is closed when the signal indicates stop, and that contact 9^a—9^b is closed when the signal indicates caution or proceed.

Associated also with each signal is a circuit interrupter designated by the reference character U with a suitable exponent. As here shown, each interrupter is a mechanical device comprising a rotatable commutator 12 of conducting material having its periphery provided with a plurality of teeth 12^b. The space between each two adjacent teeth is filled with a segment 12^a of insulating material. A fixed contact 13 is arranged to engage the segments 12^a and the teeth 12^b alternately as the commutator revolves. The commutator 12 is arranged to be rotated at a uniform speed by some suitable means such as a motor 14 constantly supplied with energy from a suitable source such as alternator M over line wires 3 and 3^a.

Each track transformer is supplied with alternating current from a line transformer designated by the reference character H with an exponent corresponding to the location and having a primary winding 8 constantly connected with line wires 3 and 3^a.

Referring particularly to the apparatus located at point B, when signal S^B indicates stop, primary 6 of track transformer T^B is connected directly with secondary 7 of line transformer H^B through contact 9^a—9^a. Under these conditions alternating current is continuously supplied to section A—B. When, however, signal S^B displays a proceed or a caution indication, contact 9^a—9^b is closed, so that transformer T^B is supplied with energy from transformer H^B through commutator 12 and contact 13 of the interrupter U^B. This commutator serves to periodically interrupt the alternating current and the parts are so designed and pro-

- portioned that the frequency of the current supplied by alternator M is greater than the frequency of interruption of contact 12-13. Under these conditions section A-B is supplied with energy in the form of a series of groups of impulses each group made up of a plurality of cycles of alternating current and each group separated from the preceding group by a time interval.
- 10 The actual frequencies used may have any reasonable values, but for purposes of explanation I will assume that the frequency of the uninterrupted alternating current is 300 cycles per second, and that the frequency 15 of the interruptions is 15 cycles per second, that is, 15 groups per second.
- As shown in the drawing a train indicated diagrammatically at V' occupies the section to the right of point C. Signal S^c is therefore at stop and section B-C is being supplied with uninterrupted alternating current at 300 cycles per second. Signal S^b is at caution and signal S^a is at proceed, and so section A-B and the section 25 to the left of point A are each supplied with alternating current of 300 cycles per second interrupted at the rate of 15 groups per second.
- I will now proceed to explain the train 30 carried apparatus by means of which the trackway circuits hereinbefore described control the train governing means.
- Located at some convenient place upon the locomotive, as in advance of the first 35 axle, is a pick-up device comprising two windings 13 and 13^a disposed in inductive relation with the two track rails and connected in series so that voltages induced in the two windings 13 and 13^a, by an alternating current which flows in opposite directions in the two track rails at an instant, are additive.
- The reference character D designates a 40 vibration relay comprising a magnetizable core 16 carrying a winding 15. A polarized vibratable armature 17 of magnetizable material has its left hand end rigidly fastened to the core 16 and its right end free to swing back and forth adjacent the other end of the core 16. Winding 15 of relay D is connected in series with the windings 13 and 13^a and the circuit is tuned to resonance at 300 cycles per second by means 45 of condenser 62. Furthermore armature 17 is tuned, by means of weight 17^a, to mechanical resonance at a frequency of 300 cycles per second. A fixed contact 17^b coacts with the free tip of armature 17 so that contact 17-17^b is closed once during each oscillation of the armature when the relay is 50 energized with current at a frequency of 300 cycles per second. A transformer E is provided with a primary winding 19 connected in series with a suitable source of direct current such as a battery 18, and contact 17-17^b. The secondary 20 of transformer E is connected, through a suitable rectifier 21, with winding 15 of a second vibration relay F, similar to relay D, but having its armature 17 tuned to mechanical resonance at the frequency of the groups of impulses supplied to the trackway, that is, at 15 cycles per second. An ordinary electromagnetic relay 25 is inserted in series with relay F for reasons which will appear 75 hereinafter. Contact 17-17^b of relay F controls the supply of direct current from battery 39 to primary 22 of transformer J as will be clear from the drawing, and a direct current impulse is therefore delivered to 80 transformer J 15 times each second when relay F is operating. The secondary 23 of transformer J supplies energy through a rectifier 24 to a second electromagnetic relay 26.
- The two electromagnetic relays 25 and 26 85 control train governing means which may be of any suitable form, and as here shown comprises three separate electric lamps G, Y and R arranged when lighted, to indicate proceed, caution and stop, respectively.
- When relay 26 is energized, current flows from a suitable source of energy such as a battery 27, through wire 28, front contact 29 of relay 26, wire 30, lamp G, and wire 31 back to battery 27. When this circuit is closed lamp G is energized and the train receives a proceed indication. When relay 25 is energized, but relay 26 is de-energized, current flows from battery 27, through wire 28, back contact 29 of relay 26, wire 32, front contact 33 of relay 25, wire 34, caution lamp Y and wire 31 back to battery 27. When this circuit is closed lamp Y is lighted and a caution indication is displayed on the train. When, however, relay 25 is de-energized, current flows from battery 27, through wire 35, back contact 36 of relay 25, wire 37, lamp R, and wire 31 back to battery 27. Under this condition lamp R is lighted to display a stop indication on the train.
- As illustrated in the drawing, train V², 110 equipped with the train carried apparatus just described, occupies the section to the left of point A, which section is supplied with 300 cycle alternating current interrupted 15 times per second. Relay D is therefore energized in such manner that its armature 17 vibrates at the rate of 300 cycles per second, which vibrations are interrupted 15 times per second. Each vibration of armature 17 causes an impulse in the primary winding 19 of transformer E, and hence there is induced in the secondary 20 of this transformer a series of groups of alternating current impulses, the frequency of these groups being 15 per second. The interrupted alternating current so created is rectified by rectifier 21 and hence the current supplied to winding 15 of relay F is pulsat-
- 115 120 125 130

ing in character. The pulsations of 300 cycles per second will not affect the armature 17 of relay F, but each group will cause this armature to swing, and the relay therefore operates to vibrate its armature at 15 cycles per second. As a result pulsating direct current of 15 impulses per second is fed to primary 22 of transformer J. The resulting alternating current in secondary 23 is supplied through rectifier 24, in the form of pulsating direct current, to relay 26, which relay becomes energized. It should be stated that although the supply of current to relay 25 is interrupted 15 times per second, the relay has a sufficient time interval to bridge over this period of de-energization and relay 25 therefore keeps its front contacts closed. Proceed lamp G is then lighted and the train receives a proceed indication.

Train V² will continue to receive a proceed indication throughout section A-C. When the train enters section B-C, the uninterrupted 300 cycle current will continue to energize relay D. The energy now supplied to relay F is uninterrupted pulsating direct current having a periodicity of 300 cycles per second. Relay F does not respond to this frequency and hence the armature is at rest and relay 26 is de-energized. Relay 25 is, however, energized by the pulsating direct current supplied thereto and hence the train receives a caution indication.

If the train V² should enter the section to the right of point C, alternating current in the rails would be shunted away from the pick-up coils of train V² by the wheels and axles of the train V'. Relay D would then be de-energized, relay F would, of course, be deprived of energy, and relays 25 and 26 would both be de-energized. Lamp R would then be lighted and the train would receive a stop indication.

Referring now to Fig. 2, the apparatus here shown is modified to embody the control of the train carried apparatus from the trackway through the medium of two alternating currents of different frequencies, one of which currents is at times interrupted in a manner similar to that explained in connection with Fig. 1. Each of the track relays K in Fig. 2 comprises two windings 10 and 11. One winding 10 of each such relay is constantly connected with the rails adjacent the entrance end of the corresponding section and the remaining winding 11 of each relay is constantly supplied with alternating current of a frequency different from that supplied by generator M. For example, the frequency supplied to winding 11 may be 60 cycles per second and as here shown current of this frequency is constantly supplied to each winding 11 from secondary 51 of a transformer designated by the reference character P with an appropriate exponent. The primary 52 of

each such transformer P is constantly supplied with alternating current of 60 cycles per second from an alternator Q over line wires 53 and 53^a. Each track relay K is provided with a plurality of contacts arranged to swing to one side or the other in response to the relative polarity of the 60 cycle currents supplied thereto.

Referring particularly to section B-C, when relay K^c is de-energized alternating 60 cycle current of one relative polarity which I shall term "reverse" relative polarity, is supplied to section B-C over contacts 54 and 55 of relay K^c and relay K^b is then energized in such direction as to swing the contacts thereon to the left hand or reverse position. When relay K^c is energized in the reverse direction 60 cycle current of the other relative polarity which I shall term "normal" relative polarity is supplied to section B-C and the contacts of relay K^b are swung to the right hand or normal position. When relay K^c is energized in the normal direction the 60 cycle current supplied to section B-C is also of normal relative polarity. Furthermore when relay K^c is de-energized 300 cycle alternating current is supplied continuously to section B-C at an intermediate point X in the section from secondary 7 of transformer H^c over contacts 56 and 57 of relay K^c. Primary 8 of transformer H is constantly supplied with 300 cycle current from generator M as in Fig. 1.

Each section is provided with an interrupter here shown as an electromagnetic device 49 provided with a circuit including its own back contact and supplied with energy from 300 cycle line wires 3 and 3^a through a rectifier 50. It follows that device 49 continuously operates to open and close contact 61. The parts may be so disposed and proportioned that the frequency of the operation of device 49 is 15 operations per second.

When relay K^c is energized in either the normal or reverse direction transformer H^c supplies 300 cycle current to section B-C, adjacent the exit end of the section over contact 61 of device 49 and contacts 58 and 59 of relay K^c. It follows then, that under these conditions section B-C is supplied with energy in the form of 300 cycle alternating current, interrupted 15 times per second to form a series of groups of impulses each group separated from the preceding group by a time interval.

In the train carried apparatus the 300 cycle track current supplies relays 25 and 26 through the medium of windings 13 and 13^a as in Fig. 1. In addition the train carried pick up device comprises two other pick up windings 38 and 38^a connected in the same manner as windings 13 and 13^a and also in inductive relation with the track rails.

A vibration relay L similar to relays D and F is provided with an armature 17 tuned to mechanical resonance at 60 cycles per second and is connected with windings 38 and 38^a

5 The circuit for relay L and including windings 38 and 38^a is tuned to resonance at 60 cycles per second by means of a condenser 62^a. The armature 17 of relay L controls the supply of energy from a battery 40 to primary 41 of a transformer O, the secondary 42 of which supplies energy to relay 44 through a rectifier 43. It will thus be clear that relay 44 is energized only when the train occupies a stretch of track which is

10 15 being supplied with 60 cycle alternating current.

The circuit for the proceed lamp now may be traced from battery 27, through wire 45, front contact 46 of relay 44, wire 28, front contact 29 of relay 26, wire 30, lamp G, and wire 31 back to battery 27. This circuit is closed only when relays 26 and 44 are energized, under which conditions a proceed indication is received on the train. When 25 relays 44 and 25 are energized but relay 26 is de-energized, a caution indication is displayed by the lighting of lamp Y, current flowing from battery 27 through wire 45, front contact 46 of relay 44, wire 28, back contact 30 contact 29 of relay 26, wire 32, front contact 33 of relay 25, wire 34, lamp Y, and wire 31 back to battery 27. When relay 25 is de-energized a circuit is completed from battery 27, through wire 35, back contact 35 40 45 36 of relay 25, wire 37, lamp R, and wire 31 back to battery 27. When this circuit is closed lamp R is lighted and the train then receives a stop indication. It should be pointed out that when relay 44 is de-energized, the left hand terminal of battery 27 is connected with wire 37 through wire 45 and back contact 46 of relay 44, and it therefore follows that the train receives a stop indication due to the lighting of lamp R when either relay 44 or 25 is de-energized.

As shown in the drawing the train V' occupies the section to the right of point C. Relay K^c is then de-energized and section B-C is supplied with continuous 300 cycle current at point X and with 60 cycle current of reverse relative polarity at point C. Relay K^b is therefore energized in the reverse direction and section A-B is supplied at point B with 300 cycle current interrupted to form 15 groups per second, and also with 60 cycle alternating current of normal relative polarity. Relay K^a is therefore energized in the normal direction and the section to the left of point A is supplied with 300 cycle current interrupted at the rate of 15 groups per second, and also with 60 cycle current of normal relative polarity.

Train V², provided with the apparatus hereinbefore explained, occupies the section to the left of point A and relays D and F

are operated, as explained in connection with Fig. 1, by the interrupted 300 cycle current. Relays 25 and 26 are therefore both energized. At the same time relay L responds to the 60 cycle current induced in windings 38 and 38^a to vibrate its armature 17. Pulsating direct current is then supplied to primary 41 from battery 40 at a periodicity of 60 impulses per second. The resulting 60 cycle alternating current supplied by secondary 42 is changed, by rectifier 43, into uni-directional current which energizes relay 44. The train then receives a proceed indication which persists as the train proceeds through section A-B. When train V² enters section B-C the continuous 300 cycle current continues to energize relay D, and hence relay 25, but relay F cannot respond to this current and relay 26 then becomes de-energized. Relay 44 is still energized and the train receives a caution indication. After the train passes point X in section B-C, the supply of 300 cycle current to windings 13 and 13^a is discontinued, such current being shunted away by the wheels and axles of train V². Relays D and 25 then become de-energized and the train receives a stop indication. If the train should enter the section to the right of point C this stop indication would continue to be displayed since both 300 cycle and 60 cycle are shunted by the wheels and axles of train V² and hence all relays 25, 26 and 44 will be de-energized. It should be noticed that any cessation of the 300 cycle current or the 60 cycle or both of them will result in a stop indication.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track, means for supplying said stretch at times with uninterrupted alternating current, means for supplying the stretch at other times with interrupted alternating current, and governing means including two vibration relays selectively responsive to said currents.

2. Railway traffic controlling apparatus comprising a stretch of railway track, means for supplying alternating current to said stretch, means for at times regularly interrupting the supply of said current, a vibration relay responsive to the presence of said alternating current in the stretch, a second vibration relay responsive to the continuity of said current, and governing means controlled jointly by said two relays.

3. Railway traffic controlling apparatus comprising a stretch of railway track, means for at times supplying energy to said stretch in the form of a series of groups of impulses 5 each group made up of a plurality of cycles of alternating current, a vibration relay responsive to said alternating current, a second vibration relay responsive to said groups, and governing means controlled 10 jointly by said relays.

4. In combination, a vibration relay, means for supplying an alternating current to said relay, means for at times breaking up said alternating current into a plurality 15 of groups each separated from the preceding group by a time interval and each group comprising a plurality of cycles of said current, a second vibration relay controlled by said first relay and having a maximum response at the periodicity of said groups, and 20 governing means controlled by said second relay.

5. In combination, a stretch of railroad track, means for supplying said stretch with 25 alternating current of one frequency, means for at times interrupting said current to form a series of groups of impulses, each impulse comprising a plurality of cycles of said current, a vibration relay, means for 30 supplying said relay with current of the frequency of said alternating current, a second vibration relay, means controlled by said first relay for supplying said second relay with current of the periodicity of said 35 groups, and governing means controlled by said second relay.

6. In combination, a stretch of railway track, means for supplying said stretch with alternating current of one frequency, means 40 for at times interrupting said current to form a series of groups of impulses, each impulse comprising a plurality of cycles of said current, a vibration relay arranged to receive energy from the trackway and tuned 45 to mechanical resonance at the frequency of said current, a second vibration relay tuned to mechanical resonance at the frequency of said groups, means for delivering a surge of uni-directional current to said second relay 50 for each operation of said first relay, and governing means controlled by said second relay.

7. In combination, a stretch of railway track, means for supplying said stretch with 55 alternating current of one frequency, means for at times interrupting said current to form a series of groups of impulses, each impulse comprising a plurality of cycles of said current, a vibration relay arranged to receive energy from the trackway and tuned 60 to mechanical resonance at the frequency of said current, a second vibration relay, means for delivering a surge of uni-directional current to said second vibration relay once for 65 each group of cycles of said alternating current.

rent, a third relay inserted in series with said second relay, and governing means controlled by said second and said third relays.

8. In combination, a stretch of railway track, means for supplying said stretch with 70 alternating current of one frequency, means for at times interrupting said current to form a series of groups of impulses, each impulse comprising a plurality of cycles of 75 said current, a vibration relay tuned to mechanical resonance at the frequency of said alternating current, a circuit for said relay in inductive relation with the trackway and tuned to electrical resonance at the frequency of said alternating current, a second 80 vibration relay, means controlled by said first relay for at times operating said second relay in synchronism with said groups, and governing means controlled by said second 85 relay.

9. In combination, a first vibration relay, means for at times supplying said first relay with alternating current, means for at times breaking up said current into a series of groups of impulses, a circuit controlled 90 by said first relay and including a source of direct current and the primary of a transformer, a second vibration relay, a circuit for said second vibration relay including a 95 rectifier and the secondary of said transformer, and governing means controlled by said second relay.

10. In combination, a first vibration relay, means for at times supplying said first relay with alternating current, means for at times 100 breaking up said current into a series of groups of impulses, a second vibration relay controlled by said first relay and arranged to be operated when such first relay is receiving said groups of impulses but not when 105 the first relay is receiving continuous alternating current, and governing means controlled by said second relay.

11. In combination, a relay having a vibratable armature, means for causing said 110 armature to vibrate continuously at times and intermittently at other times, a second vibration relay arranged to operate only when said armature vibrates intermittently, a third relay arranged to be energized when 115 said armature vibrates continuously or intermittently, and governing means controlled by said second and third relays.

12. In combination, a stretch of railway track, means for supplying alternating current to the rails of said stretch, means responsive to traffic conditions in advance of said stretch for at times interrupting said current to form a series of groups of alternating current impulses each group being 120 separated from the preceding group by a time interval, and governing means on a train including a first vibration relay responsive to said alternating current whether 125 continuous or intermittent and a second vi- 130

bration relay responsive to said groups of impulses.

13. In combination, a stretch of railway track, means for supplying alternating current to the rails of said stretch, means responsive to traffic conditions in advance of said stretch for at times interrupting said current to form a series of groups of alternating current impulses each group being 10 separated from the preceding group by a time interval, and governing means on a train including a first vibration relay tuned to mechanical resonance at the frequency of said alternating current, and a second vibration relay tuned to mechanical resonance 15 at the frequency of said groups.

14. In combination, a stretch of railway track, means for at times supplying said stretch with alternating current, means controlled by traffic conditions in advance of said stretch for at other times supplying said stretch with energy in the form of successive groups of impulses each group made up of a plurality of cycles of said alternating 20 current and separated from the preceding group by a time interval, a vibration relay receiving energy from the trackway and comprising a vibratable armature tuned to resonance at the frequency of said alternating current, a second vibration relay controlled by said armature and comprising a second armature tuned to mechanical resonance at the frequency of said groups, a third relay arranged to be energized when 25 said first vibration relay is being supplied with alternating current continuously or in groups, a fourth relay controlled by said second armature, and governing means controlled by said third and fourth relays.

15. In combination, a vibration relay, means for at times supplying said relay with energy in the form of a continuous series of impulses of uni-directional current and for at other times supplying the relay with 30 energy in the form of a series of groups of impulses each group separated from the preceding group by a time interval, said relay being tuned to mechanical resonance at the frequency of said groups, and governing means controlled by said relay.

16. In combination, a vibration relay, means for at times supplying said relay with energy in the form of a continuous series of impulses of uni-directional current and for at other times supplying the relay with energy in the form of a series of groups of impulses each group separated from the preceding group by a time interval, said relay being tuned to mechanical resonance at 35 the frequency of said groups, a second relay arranged to be energized when said vibration relay is being supplied with such continuous impulses, a third relay controlled by the vibration relay, and governing means controlled by said second and third relays.

17. In combination, two vibration relays tuned to mechanical resonance at different frequencies, means for at times continuously operating one of said relays, means for at other times intermittently operating the said relay and continuously operating the second relay, and governing means controlled by 40 said relays.

18. In combination, a stretch of railway track, train carried apparatus comprising two vibration relays tuned to mechanical resonance at different frequencies, means responsive to traffic conditions in advance of said stretch for at times continuously operating one of said relays, means for at other times intermittently operating the said first relay and continuously operating the second relay, and governing means controlled by 45 said relays.

19. In combination, a stretch of railway track, a source of alternating current of the first frequency connected at all times with the rails of the stretch, means for at times supplying said stretch with alternating current of a second frequency, means for at other times interrupting said second current to produce a series of groups of impulses each group comprising a plurality of cycles of alternating current of said second frequency and separated from the preceding group by a time interval, a first vibration relay tuned to mechanical resonance at said first frequency and arranged to receive energy from the trackway, a second vibration relay tuned to mechanical resonance at said second frequency and arranged to receive energy from the trackway, a third vibration relay controlled by said second relay and tuned to mechanical resonance at the frequency of said groups, and governing means controlled by said first and third relays.

20. In combination, a stretch of railway track, a source of alternating current at times connected directly with the rails of said stretch, a contact arranged to be alternately opened and closed, means for at other times interposing said contact between said source and the rails of the stretch, and governing means responsive to current in the trackway and comprising two vibration relays one arranged to operate when the rails are supplied with alternating current and the other arranged to operate only when such alternating current is intermittently supplied to the rails.

21. In combination, a section of railway track, means for at times supplying alternating current to the rails throughout the length of the section, means for at other times supplying the rails of a portion of the section with energy in the form of a series of groups of impulses each group made up of a plurality of cycles of said alternating current, a vibration relay receiving energy from the trackway and set into operation by 50

- said alternating current, and a second vibration relay controlled by said first relay and tuned to mechanical resonance at the frequency of said groups.
- 5 22. In combination, a section of railway track, means for supplying alternating current to the rails of a portion only of the section when traffic conditions in advance are dangerous, means effective when traffic conditions in advance are safe for supplying the rails throughout the length of the section with energy in the form of a series of groups of impulses each group made up of a plurality of cycles of said alternating current, a vibration relay receiving energy from the trackway and set into operation by said alternating current, and a second vibration relay controlled by said first relay and tuned to mechanical resonance at the frequency of said groups, and governing means on a train controlled by said relays.
- 10 23. In combination, a section of railway track, means for at all times supplying the rails of the section with alternating current of a first frequency throughout the length of the section, means for supplying the rails of a portion only of the section with alternating current of a second frequency when traffic conditions in advance are dangerous, means effective when traffic conditions in advance are safe for supplying the rails throughout said section with energy in the form of a series of groups of impulses each group made up of a plurality of cycles of such second frequency and each group separated from the preceding group by a time interval, a first vibration relay receiving energy from the trackway and tuned to mechanical resonance at said first frequency, a second vibration relay receiving energy from the trackway and tuned to mechanical resonance at said second frequency, a third vibration relay controlled by said second relay and tuned to mechanical resonance at the frequency of said groups, and governing means controlled by said three relays.
- 15 24. In combination, a section of railway track, means for at all times supplying the rails of the section with alternating current of a first frequency throughout the length of the section, means for supplying the rails of a portion only of the section with alternating current of a second frequency when traffic conditions in advance are dangerous, means effective when traffic conditions in advance are safe for supplying the rails throughout said section with energy in the form of a series of groups of impulses each group made up of a plurality of cycles of such second frequency and each group separated from the preceding group by a time interval, a first vibration relay tuned to mechanical resonance at said first frequency and provided with a circuit located
- 20 in inductive relation with the track rails and tuned to resonance at said first frequency, a second vibration relay tuned to mechanical resonance at said second frequency and provided with a circuit located in inductive relation to the track rails and tuned to resonance at said second frequency, a third vibration relay controlled by said second relay and tuned to resonance at the frequency of said group, three auxiliary relays one controlled by each said vibration relay, and governing means controlled by said auxiliary relays.
- 25 25. In combination, a stretch of railway track, a source of alternating current at times connected directly with the rails of said stretch, a contact arranged to be alternately opened and closed, means for at other times interposing said contact between said source and the rails of the stretch, two vibration relays one arranged to be operated when the rails are supplied with alternating current and the other arranged to operate only when such alternating current is intermittently supplied to the rails, and governing means on a train controlled solely by said vibration relays.
- 30 26. In combination, a stretch of railway track, a source of alternating current at times connected directly with the rails of said stretch, a mechanical circuit interrupter, means for at other times interposing said contact between said source and the rails of the stretch, and governing means responsive to current in the trackway and comprising two vibration relays one arranged to operate when the rails are supplied with alternating current and the other arranged to operate only when such alternating current is intermittently supplied to the rails.
- 35 27. In combination, a stretch of railway track, means for supplying said stretch at times with alternating current and at other times with periodically interrupted alternating current, a relay selectively responsive to current of the frequency of said periodic interruptions, a second relay selectively responsive to the frequency of said alternating current for supplying said first relay with current of the frequency of said periodic interruptions, and governing means controlled jointly by said two relays.
- 40 28. Railway traffic controlling apparatus comprising a stretch of railway track, means for at times supplying energy to said stretch in the form of a series of groups of impulses of alternating current, a first vibration relay responsive to said alternating current, and a second vibration relay responsive to said group.
- 45 29. In combination, a stretch of railway track, means for at times supplying said stretch with uninterrupted alternating current, means for at other times mechanically

- interrupting said current at regular periods, and traffic governing means including two relays selectively responsive to said alternating current and to said periodically interrupted current respectively.
30. In combination, a stretch of railway track, means for at times supplying said stretch with uninterrupted alternating current, means for at other times mechanically interrupting said current at regular periods, two train carried relays selectively responsive to said alternating current and to said periodically interrupted current respec-
- 10 tively, and governing means on the train controlled by said relays.
31. In combination, a stretch of railway track, means for at times supplying said stretch with uninterrupted alternating current, means for at other times mechanically interrupting said current at regular periods, and traffic governing means including a relay responsive to said periodically interrupted current but not to said current.

In testimony whereof I affix my signature.

HAROLD O. HOLTE.
